At the

UNITED STATES PATENT OFFICE

STERLING H. CAMPBELL, OF ST. LOUIS, MISSOURI, ASSIGNOR TO WESTERN RAILWAY EQUIPMENT COMPANY, OF ST. LOUIS, MISSOURI, A CORPORATION OF MISSOURI

JOURNAL BEARING FOR RAILWAY CARS

Application filed August 6, 1930. Serial No. 473,336.

My invention relates to journal bearings for railway cars and particularly to a wedge provided with tool engaging means for facilitating the prying down of the front end of the wedge to permit its withdrawal from the journal box. In the specific forms shown in the drawings my invention contemplates improvements in the journal bearing shown and described in my co-pending application Serial No. 286,086 filed June 18, 1928.

In the accompanying drawings, which illustrate two forms of journal bearings made in accordance with my invention, Figure 1 is a longitudinal section; Figure 2 is an enlarged front elevation of the wedge; Figure 3 is a section taken on the line 3—3 of Figure 2; Figure 4 is partly a front elevation and partly a section taken on the line 4—4 of Figure 1; Figure 5 is a sectional view of a modified form of wedge taken on the line 5—5 of Figure 6; Figure 6 is a front elevation of the modified form of wedge; and Figure 7 is a view similar to Figure 4 but showing the modified form of wedge.

Referring to Figures 1 to 4, 7 indicates a journal box of the usual type provided at its forward end with a pair of lateral depending lugs 8 engaging with the upper part of the front face 9 of the wedge 10 to retain the wedge in position in the box. The wedge is of the type shown in my co-pending application above referred to, having its upper face 11 longitudinally curved to permit rocking movement relative to the journal box, its lower face 12 shaped to conform to the upper face of the brass 13 and having its front face 9 extended downwardly to form a curved flange, providing a pair of lateral hand holds 14 for use in withdrawing the wedge from the journal box. The flange is separated from the bearing portion of the under face of the wedge by a recess 15 and the front edge of the brass is held against forward movement by means of an upwardly projecting flange 16 on the rear end of said brass and contacting with the rear end of the wedge. The lower face of the brass rests upon the axle 20 in the usual manner.

In order to provide the front face of the wedge with tool engaging shoulders cooper-

ating with the flanges or lugs 8 as fulcrums to pry down the wedge to disengage it from the flanges, I form in each of the hand-holds an opening 17 positioned directly below the corresponding flange 8. As these openings cannot be forged in the wedge, I form them by drilling through the hand-holds and into the recess 15 which is provided with extensions 18 to permit clearance for the end of the drill which would otherwise strike the walls of the recess and be deflected laterally.

In Figures 5, 6 and 7, I have shown a modified form in which the tool engaging shoulder, instead of being provided by the lower edge of a hole in each hand-hold, is provided by the upper face of a lug 19 projecting forwardly from the hand-hold directly below the corresponding flange 8.

In disassembling the bearing the journal box is jacked up or otherwise raised to remove the weight of the car from the axle. When this is done the wedge usually adheres to the box and is raised with it so that its front end remains in contact with flanges 8. While the hand-holds as set forth in my prior application provides means for drawing the wedge forwardly out of the journal box, they do not provide effective means for lowering the wedge out of engagement with the flanges 8 when it adheres firmly to the box. In such case a pry bar is used, its lower forward edge resting on the shoulder formed by the lower edge of the hole 17 in the forms shown in Figures 1 to 4, or by the upper face of the lug 19 in the forms shown in Figures 5 to 7, the upper edge of the bar bearing on the flange 8 as a fulcrum. By raising the outer end of the bar even the most tightly adhering wedge is easily pried down out of engagement with the retaining flange 8 so that it may be drawn out by means of the hand-holds.

Having fully described my invention, what I claim as new and desire to secure by Letters Patent of the United States is:

1. A wedge for journal bearings having an upper face for cooperating with a journal box and a lower face for contacting with a brass, said wedge having at its forward end a downwardly projecting flange forming a hand-hold, said flange having therein an

opening forming a tool engaging shoulder situated at one side of the center line of the wedge.

2. A wedge for journal bearings having an upper face for cooperating with a journal box and a lower face for contacting with a brass, said wedge having at its forward end a downwardly projecting flange forming a hand-hold, said flange having thereon a forwardly projecting lug forming a tool engaging shoulder situated at one side of the center line of the wedge.

3. In a device of the class described, the combination with a journal box having a bearing face on the under side of its top, of a wedge having a longitudinally curved upper bearing face cooperating with said box bearing face, said wedge being provided at its forward end with a downwardly projecting flange forming a hand-hold, said flange being provided with an upwardly facing tool engaging shoulder situated substantially below the lowest point of said upper wedge bearing face, whereby said wedge may be lowered out of engagement with the box by a tool bearing on said shoulder and fulcruming on the forward part of the box top.

4. In a device of the class described, the combination with a journal box having a bearing face on the under side of its top, of a wedge having a longitudinally curved upper bearing face cooperating with said box bearing face, said wedge being provided at its forward end with a downwardly projecting flange forming a hand-hold, said flange being provided with a recess extending inwardly from its front face and forming a tool engaging shoulder, whereby said wedge may be lowered out of engagement with the box by a tool bearing on said shoulder and fulcruming on the forward part of the box top.

In testimony whereof, I hereunto affix my signature, this 4th day of August, 1930.

STERLING H. CAMPBELL.
